UNITED STATES PATENT OFFICE

RICHARD HERZ, OF FRANKFORT-ON-THE-MAIN, WILHELM BAUER, OF WIESDORF/NIEDERRHEIN, AND NORBERT STEIGER, OF FRANKFORT-ON-THE-MAIN, GERMANY, ASSIGNORS TO GENERAL ANILINE WORKS, INC., OF NEW YORK, N. Y., A CORPORATION OF DELAWARE

PROCESS FOR MANUFACTURING PHENYLTHIOLYCOLIC ACIDS CONTAINING HALOGEN AND ALKYL GROUPS IN THEIR MOLECULE

No Drawing. Application filed November 8, 1927, Serial No. 230,922, and in Germany November 24, 1926.

Phenylthioglycolic acids, containing halogen and alkylgroups in their molecule, are important intermediates for the production of hydroxythionaphthene derivatives, containing halogen and alkylgroups in their molecule, and of the corresponding dyestuffs of the thioindigo- and thionaphthenindolindigo type. They are hitherto mostly prepared from the corresponding aminohalogenalkylbenzenes by converting them into the xanthogenic esters according to Leukhardt's reaction, saponifying the latter and condensing the mercaptan compounds thus obtained with monochloroacetic acid. This process is in many cases rather complicated and the products obtained by it are often lacking in yield and purity. Furthermore the starting materials for this process are obtained by nitration and subsequent reduction of the corresponding halogenalkylbenzenes. It is known, that the nitration process of these hydrocarbons yields in nearly all cases a mixture of isomeric bodies, from which the desired products must be isolated by a tedious method. It is therefore a demand for a process which allows to manufacture these important phenylthioglycolic acids containing halogen and alkylgroups in their molecule by a technically simple method.

We have found such a process which consists in treating halogenalkylbenzenes with chlorosulfonic acid at temperatures below 100°, reducing the halogenalkylbenzenesulfochlorides thus formed to the corresponding mercaptan compounds and condensing the latter with monochloroacetic acid. In this manner phenylthioglycolic acids, containing halogen and alkylgroups in their molecule, are obtained with a very satisfactory yield in an excellent state of purity. In contradistinction to the nitrating process of halogenalkylbenzenes the introduction of the sulfochloride group into the molecule of these hydrocarbons runs almost uniformly. This is a surprising fact, because, as it is known, when subjecting toluene to the action of chlorosulfonic acid always a mixture of isomeric ortho- and para- compounds is obtained. It should be therefore expected, that when subjecting instead of toluene halogen-

alkylbenzenes to the reaction also a mixture of isomeric sulfochlorides should be obtained. But apparently in these halogenalkylbenzenes only the halogen has a directing influence for the entrance of the sulfochloride group, locating it almost entirely into the para-position to one halogen.

Our present process gives particularly good results, when starting from benzenederivatives of the formula:

60

65

wherein X means halogen or CH₃, whereby thioglycolic acid derivatives of the formula:

70

75

(wherein X has the same signification) are obtained in a very satisfactory yield and in an excellent state of purity.

In order to further illustrate our invention the following examples are given, the parts being by weight and all temperatures in centigrade degrees, but we wish to be understood that our invention is not limited to the examples given, nor to the exact conditions stated therein.

Example 1

(a) Production of 1-methyl-2,4-dichlorobenzene-5-sulfochloride of the formula:

80

85

At about 30-35° 8.1 parts of 1-methyl-2,4-dichlorobenzene (boiling point 194°) are slowly introduced while stirring into 32 parts of chlorosulfonic acid. Then the mass is kept 100

for some hours at about 60° while stirring. After cooling down it is poured on ice and the reaction product separates in crystalline form. The new 1-methyl-2,4-dichlorobenzene-5-sulfochloride thus formed melts in a pure state at 71°.

(b) Production of 1-methyl-2,4-dichlorobenzene-5-mercaptop of the formula:

10

15

26 parts of the aforesaid sulfochloride are introduced into a mixture of about 55 parts of sulfuric acid of 66° Bé. and 120 parts of water and slowly about 30 parts of zinc dust are added while stirring; the temperature of the mass is advantageously about 80°. The reduction process runs smoothly and after cooling down the mercaptan compound formed separates as a crystalline mass; it is isolated by filtration and can directly be used for the production of the thioglycolic acid compound. In order to obtain it in a pure form it may be subjected to a steam distillation.

30 (c) Production of 1-methyl-2,4-dichlorobenzene-5-thioglycolic acid of the formula:

35

40 19.3 parts of the aforesaid mercaptan are dissolved in dilute caustic soda solution and at ordinary temperature 10.7 parts of monochloroacetic acid in form of its sodium salt are added. The mixture is digested, until a test does not show a yellow coloration with a solution of lead acetate. The 1-methyl-2,4-dichlorobenzene-5-thioglycolic acid formed may be isolated in form of the difficultly soluble salts of sodium or calcium by adding common salt or chalk to the solution, or it may be separated as free acid by acidifying the cooled solution. In a pure state it melts at 112°.

Example 2

55 (a) Production of 1,4-dimethyl-2-chlorobenzene-5-sulfochloride of the formula:

60

At about 30-35° 7 parts of 1,4-dimethyl-2-chlorobenzene (boiling point 192°) are slowly introduced into about 30 parts of chloro-

sulfonic acid. Then the mass is kept for some hours at about 60° while stirring. After cooling down it is poured on ice and the 1,4-dimethyl-2-chlorobenzene-5-sulfochloride formed separates in a crystalline form. It is a new compound, unknown hitherto. It may be directly used for the further process. If recrystallized from acetone it melts at 50°.

(b) Production of 1,4-dimethyl-2-chlorobenzene-5-mercaptop of the formula:

75

80

24 parts of the aforesaid sulfochloride compound are introduced into a mixture of about 55 parts of sulfuric acid of 66° Bé. and 120 parts of water and slowly about 30 parts of zinc dust are added while stirring; the mass is kept for some time advantageously at 80°. The reduction process runs smoothly and after cooling down the 1,4-dimethyl-2-chlorobenzene-5-mercaptop separates as a crystalline mass; it is isolated by filtration and can be directly used for the production of the thioglycolic compound. In order to obtain it in a pure state it may be subjected to a steam distillation.

(c) Production of 1,4-dimethyl-2-chlorobenzene-5-thioglycolic acid of the formula:

95

100

105 17.3 parts of the aforesaid mercaptan are dissolved in dilute caustic soda solution and at ordinary temperature 10.7 parts of monochloroacetic acid in form of its sodium salt are added. When the reaction is complete, the 1,4-dimethyl-2-chlorobenzene-5-thioglycolic acid formed may be isolated in form of its difficultly soluble salts or as free acid by acidifying the solution. In a pure state it melts at 96°.

110 When starting from 1,4-dimethyl-2-bromobenzene in the same manner the 1,4-dimethyl-2-bromobenzene-5-thioglycolic acid can be obtained.

120

We claim:

1. A process for manufacturing phenylthioglycolic acids containing halogen and alkyl groups in their molecule, which process comprises treating halogenalkylbenzenes with chlorosulfonic acid at temperatures below 100°, reducing the halogenalkylbenzenesulfochlorides thus formed to the corresponding mercaptan compounds and condensing the latter with monochloroacetic acid.

130

2. A process for manufacturing phenylthioglycolic acids of the general formula:

10 in which formula X means halogen or CH_3 , which process comprises treating benzene-derivatives of the formula:

20 in which formula X has the aforesaid significance, with chlorosulfonic acid at temperatures below 100° , reducing the halogen-alkylbenzenesulfochlorides thus formed to the corresponding mercaptan compounds and condensing the latter with monochloroacetic acid.

3. A process for manufacturing phenylthioglycolic acids of the general formula:

40 in which formula X means chlorine or CH_3 , which process comprises treating benzene derivatives of the formula:

45 in which formula X has the aforesaid significance, with chlorosulfonic acid at temperatures below 100° , reducing the chloromethylbenzenesulfochlorides thus formed to the corresponding mercaptan compounds and condensing the latter with monochloroacetic acid.

4. As new compounds phenylsulfochlorides of the formula:

60 in which formula X means chlorine or CH_3 , which compounds are when dry crystalline powders, having a definite melting point, which compounds are substantially identical

with products obtainable by treating benzene-derivatives of the formula:

75 in which formula X has the aforesaid significance, with chlorosulfonic acid at temperatures below 100° .

5. As a new compound 1,4-dimethyl-2-chlorobenzene-5-sulfochloride of the formula:

85 melting in a pure state at 50° , being substantially identical with a product obtainable by treating 1,4-dimethyl-2-chlorobenzene with chlorosulfonic acid at temperatures below 100° .

6. The process of manufacturing phenylsulfochlorides of the general formula:

90 wherein X represents halogen or methyl which process comprises treating a compound of the general formula:

105 wherein X represents halogen or methyl, with chlorosulfonic acid at a temperature below 100° C .

7. The process of manufacturing phenylsulfochlorides of the general formula:

120 wherein X represents chlorine or methyl which process comprises treating a compound of the general formula:

wherein X represents chlorine or methyl, with chlorosulfonic acid at a temperature below 100° C.

8. The process which comprises introducing at a temperature of about 30-35° C. about 5 7 parts of 1,4-dimethyl-2-chlorobenzene into about 30 parts of chlorosulfonic acid, keeping the mass for some hours at a temperature of about 60° C. while stirring, and isolating the resulting 1,4-dimethyl-2-chlorobenzene-5-sulfochloride.

10 In testimony whereof, we affix our signatures.
